BASE MOUNT FOR ANTENNA MASTS

Howard D. Vogt and Oliver J. Kieffer, Flint, Mich.

Application April 26, 1951, Serial No. 223,004

1 Claim. (Cl. 248—43)

1

This invention relates to base mounts for antenna masts and more particularly to base mounts constructed and arranged to aid in the erecting and lowering of antenna masts.

The primary object of the invention is to provide an antenna mast mount for supporting an antenna mast and a lever held at an angle relative to one another for raising and lowering the antenna mast upon lowering or raising of the lever.

Another object of the invention is to provide an antenna mast mount as set forth above wherein pivotally arranged sockets on the mount detachably receive ends of the mast and lever and permit removal of the lever after erection of the antenna mast.

A further object of the invention is to provide an antenna mast mount in accordance with the preceding objects wherein guy wires may be attached to the mast and to the roof of a building prior to erecting the mast for controlling the position of the mast during erection, thereby eliminating the services of considerable manual help in erecting the mast.

It is also an object of the invention to provide an antenna mast mount of the above-indicated character which is simple and substantial in construction, which can be manufactured economically, and which will be thoroughly efficient and practical in use.

These, together with various auxiliary features and objects of the invention which will later become apparent as the following description proceeds, are attained by the present invention, preferred embodiments of which have been illustrated, by way of examples only, in the accompanying drawings, wherein:

Figure 1 is a partial perspective view of a building showing the improved antenna mast mount in use with an antenna mast erected;

Figure 2 is a similar view of the same prior to the erection of the antenna mast;

Figure 3 is an enlarged perspective view of the mount and lever in the position shown in Figure 2;

Figure 4 is an enlarged perspective view of the mount in the position with the antenna mast erected and the lever removed;

Figure 5 is a vertical sectional view of the parts in the position shown in Figure 4;

Figure 6 is a vertical section taken on line 6—6 of Figure 5;

Figure 7 is an elevational and sectional view

2

showing the mount attached to a side of an inclined roof;

Figure 8 is a perspective view of a modified form of the invention showing the mount attached to a roof and in the position before erection of the antenna mast; and

Figure 9 is a similar view of the form of invention shown in Figure 8 with the parts in position after the antenna mast has been erected.

Referring now more specifically to the accompanying drawings wherein like numerals designate similar parts throughout the various views, attention is directed first to Figures 1 and 2 wherein it will be seen that there is indicated at 10 a building with a gable roof 11 upon which a base mount 12 and two sets of guy wires 13 and 14 support an antenna mast 15 in erected position, as shown in Figure 1, and during the process of erecting, as shown in Figure 2. Each set of guy wires 13 and 14 consists of four wires attached to the roof 11 by eye bolts 16, one every ninety degrees around the mast when said mast is completely erected. All of the wires 13 are attached to a rotatable ring 17 located on the 20 mast at a higher elevation than another rotatable ring 18 located on the mast to which the wires 14 are attached.

The improved antenna mast mount 12 forming the subject matter of the invention illustrated in Figures 1 through 7 consists generally of a roof-attachment base 19 rotatably supporting on a vertical axis a substantially U-shaped bracket 20 which pivotally supports between the opposite upstanding legs thereof on a horizontal axis, a 30 pair of socket members 21 and 22 into one of which is received an end of the mast 15, and into the other, an end of a lever 23.

On the opposite end of the lever 23 from that received in the socket 22 is secured a cap 24 which has an eye 25 on the end thereof through which are passed a guy wire 13 and a guy wire 14 connected to the mast 15 and temporarily attached to the side of the lever 23 by a clamp 26. These two guy wires are the only ones that are not attached to the roof prior to erecting the mast, and it is these two guy wires that are used for the purpose of raising the mast upon lowering the lever. The other guy wires stabilize the mast during the erection thereof. Ropes 27 tied in eyes 28 on opposite sides of the cap 24 and in eye bolt 16 on the roof 11 support the lever 23 against side movement during a pull thereon to raise the mast and are disconnected after the mast has been erected. Another eye 29 on the cap 24 has 50 a chain 30 attached thereto which is dropped to

the ground, as shown in Figure 2, where it may be conveniently engaged for applying a pull thereto for lowering the lever and raising the mast. After the mast is raised to a vertical position, the pair of guy wires 13 and 14 clamped to the lever 23 are disconnected from the lever and are attached to their respective eye bolts 16 on the roof.

The roof-attachment base 19 is constructed of a heavy plate bent in substantially inverted U-shaped formation, as indicated by the numeral 31, and with outwardly directed feet 32 provided with a number of holes through which screws or bolts 33 are extended for attachment to the roof. Slots 34 are provided at the bends where the feet 32 connect with the opposite sides of the inverted U-shaped portion 31 of the attaching base for facilitating bending of the feet at proper angles according to the pitch or slant of the roof.

Welded or otherwise attached to the top of the inverted U-shaped portion 31 is a heavy reinforcing plate 35 which, together with the top wall of said inverted U-shaped portion and bight portion 36 of the U-shaped bracket 20, has aligned holes 37 therein through which a bolt 38 extends for rotatably attaching the U-shaped bracket 20 to the roof attachment base 19. A nut 39 with a lock washer on the lower end of the bolt 38 serves the purpose of binding the engaging faces of the plate 35 and bracket 20 against turning movement relative to one another.

On the inner surfaces of the opposite side legs 40 of the U-shaped bracket are secured by welding, or any other method, reinforcing spacers 41 that engage outer side faces of a forked extension 42 on the socket member 21, while a single extension 43 on the socket member 22 is received in the forked extension 42. Through aligned openings in the side legs 40, spacers, 41, forked extension 42, and extension 43, a bolt 44 extends for pivotally connecting the socket members 21 and 22 to the U-shaped bracket. A nut 45 with a lock washer is threaded on the bolt 44 for retaining said bolt in place. Extending downwardly from the interior of the socket 21 is a small port 46 for permitting drainage of rain water or other substances that may possibly enter said socket.

The walls of the sockets 21 and 22 have transversely aligned openings 47 and 48, respectively, therein for alignment with openings in the antenna mast 15 and lever 23 and through which bolts 49 and 50 are temporarily placed and retained by wing nuts 51 and 52, respectively, for preventing accidental disengagement of parts during erection of the mast. After the mast is secured in erected position, the bolts 49 and 50, together with the lever 23, are removed, and a set screw 53 in the wall of the socket 21 holds the mast 15 against turning in said socket.

By referring now to the form of invention illustrated in Figures 8 and 9, it will be observed that the lever socket member, indicated by the numeral 22^a, instead of being pivotally connected to the U-shaped bracket 20^a at the pivotal connection of the antenna mast socket member 21^a to said bracket, is pivotally supported on the side of the socket member 21^a by positioning the extension 43^a of the socket member 22^a between a pair of spaced lugs 58 on the socket member 21^a and extending a bolt 59 through aligned openings in the lugs 58 and extension 43^a. With this arrangement, the socket member 22^a may also

be removed along with the lever 23^a after erection of the antenna mast 15^a by merely removing the bolt 59.

In operation, the base 19 of the mount is secured in proper position on the roof 11 by the screws or bolts 33 after which the mast 15 and lever 23 are inserted in the sockets 21 and 22, respectively, and secured in place by the bolts 49 and 50. Three guy wires of each set 13 and 14 are attached to the rotatable rings 17 and 18 on the mast 15 and to the eye bolts 16 secured to the roof, while the other guy wire of each set 13 and 14 is passed through the eye 25 on the lever 23 and is temporarily secured to the lever by the clamp 26 for holding an angled relationship of the lever to the mast. Stabilizing ropes 27 for the lever are then tied to the eyes 28 on the lever and to eye bolts 16. The free end of the chain 30 is then dropped to the ground with the parts in the positions shown in Figure 2.

To erect the mast, a pull on the chain 30 will lower the upper end of the lever and raise the mast while the guy wires 13 and 14 attached to the roof and the ropes 27 also attached to the roof will stabilize the mast and lever during the erection of the mast. When the mast is in a vertical position, the guy wires 13 and 14, temporarily clamped to the lever, are disconnected and secured to their respective eye bolts 16, thus completing the supporting of the mast in erected position. By then pulling the lever sidewise, the mast may be turned on the bolt 38 for pointing the antenna bars on the mast in directions for proper reception. Next, the nut 39 is tightened to hold the mast against further turning movement. By then tightening the set screw 53 and removing the bolts 49 and 50 and lever 23, the erection of the mast is completed.

To lower or remove the mast for adjustments or repairs, the procedure just described is reversed; thus, it can be seen that two workmen may conveniently and effectively erect or lower the antenna mast with the least exertion and with less likelihood of an accident.

In view of the foregoing description taken in conjunction with the accompanying drawings, it is believed that a clear understanding of the construction, operation, and advantages of the device will be quite apparent to those skilled in this art. A more detailed description is accordingly deemed unnecessary.

It is to be understood, however, that even though there are herein shown and described preferred embodiments of the invention, various changes may be made without departing from the spirit and full intendment of the invention.

What is claimed is:

An antenna mast mounting and erecting device comprising a base for attachment to a building roof or other structure, a substantially U-shaped bracket with its bight portion rotatably connected to said base for movement of said bracket about a vertical axis on said base and with the spaced legs of said bracket extending upwardly, a socket member having a forked extension thereon pivotally supported between the legs of said U-shaped bracket for movement about a horizontal axis while the socket thereof receives the lower end of an antenna mast, and a second socket member having an extension thereon also pivotally connected to said bracket and arranged between the forked extension of said first-mentioned socket member, said sec-

5

ond-mentioned socket member being adapted to temporarily receive in the socket thereof one end of a lever which is temporarily connected to the antenna mast.
